RESILIENT BEARER FOR OFFSET PRESSES

Lassio M. Stempel, New York, N. Y., assignor, by
mesne assignments, to R. Hoe & Co., Inc., New
York, N. Y., a corporation of New York

Application June 13, 1946, Serial No. 676,516

9 Claims. (Cl. 101—217)

1

This invention relates to printing machines and more particularly to means for eliminating vibration of the printing cylinders thereof.

In lithographic offset printing machines the blanket cylinder is covered with a transfer surface or blanket, of rubber or similar material, attached to the surface of the cylinder. A gap is left in the surface of the cylinder at the points of attachment. During operation of the press, when this gap is opposite the periphery of the opposing impression cylinder, the difference in pressure created causes vibration of the press. Similar effects may occur in other types of presses and cause vibration due to interruption of the surface of a plate or form cylinder and the consequent variation in pressure between such form cylinder and the impression cylinder.

The general object of this invention is to provide means for equalizing the pressure during the revolution of the cylinders, thus smoothing out the operation of the press and preventing wear and stress caused thereby.

This result is preferably accomplished by the provision of spring-loaded plungers set into the impression cylinder at the point or points where the gaps in the surface of the blanket cylinder are opposed to the periphery of the impression cylinder, and providing hardened metal rings or bearer surfaces on the ends of the blanket cylinder to be engaged by these plungers. The pressure created by the plungers, bearing against the bearer ring surface of the blanket or printing cylinder at the instant when the gap in the surface of the blanket or printing cylinder opposes the periphery of the impression cylinder, is made substantially equal to the normal pressure on the sheet or web being printed, and hence there is no reduction in the pressure between the two cylinders while the gap is passing.

It is also an object of this invention to provide a mechanism for accomplishing the above-described purposes which is simple in construction and operation and also inexpensive.

With these and other objects in view, as may appear from the accompanying specification, the invention consists in the various features of construction and combinations of parts which will be first described in connection with the accompanying drawings, showing a resilient bearer for printing presses embodying the invention in a preferred form, and the features forming the invention will be specifically pointed out in the claims.

In the drawings:

Figure 1 is a side elevation of one end of a printing couple embodying the present invention;

Figure 2 is an end elevation of the printing couple shown in Figure 1; and

Figure 3 is a section on the line 3—3 of Figure 1.

2

Referring more particularly to the drawings, in Figure 1 is illustrated a blanket roller or cylinder 1, comprising a main body 2 and having bearer ring 3' formed at each end thereof, of hardened metal or other suitable material. The main body of the cylinder is covered with a blanket 4, rubber or any other suitable material, which is wrapped around the surface of the cylinder body 2 and fastened thereto in a channel 5 formed in the cylinder body, in any suitable manner. The blanket or printing cylinder 1 is supported on an axle or shaft 6 for rotation therewith. Since the ends of each of the cylinders are the same, only one end is shown in the drawing, and the other machine parts are omitted.

As will be understood by those skilled in the art, suitable inking and plate cylinders cooperating with the blanket cylinder will be provided.

Cooperating with the above described blanket or printing cylinder 1 is an impression cylinder 10 having a main body 11 and a surface 12 formed at each end thereof. The impression cylinder is supported by a shaft 18, which shaft, as well as the shaft 6, is supported in the frame of the press in any suitable manner, not shown.

To eliminate the vibration resulting when the gap 5 in the surface of the blanket or printing cylinder 1 reaches the impression point, or in other words, is adjacent the periphery of the impression cylinder 10, spring-loaded plungers are inserted into the surface 12 of the impression cylinder 10, extending outwardly therefrom and contacting the surface of the bearer ring or surface 3' of the blanket cylinder during rotation of the cylinders. The plungers 13 are so located in the surface 12 as to contact the bearer surface 3' at the same time as the gap 5 is adjacent the surface of the cylinder 10, creating pressure between the two cylinders to offset the lack of pressure incident to the passing of the gap in the surface of the blanket cylinder.

The plungers 13 are located in bores 14 formed in the cylinder 10, with their outer ends protruding beyond the peripheral surface thereof. Openings 16 are formed in the bodies of the plungers 13, through which pins 15 extend. The pins 15 are of smaller diameter than the openings 16 and are embedded in or otherwise rigidly affixed to the body of the cylinder 10. The difference in diameter between the openings 16 and the pins 15 allows the plungers to reciprocate within the passage or bore 14 sufficiently to bring their outer ends slightly beyond the periphery of the impression cylinder. A spring 17 is located within the bore 14 and bears against the inner ends of the plungers 13, exerting outward pressure thereon.

As the cylinders 1 and 10 rotate, one of the plungers 13 will contact the surface of the bearer ring 3' each time the gap in the surface of the resiliently covered cylinder 1 comes opposite the

surface of the impression cylinder 10, the plungers being so arranged and located, according to the sizes of the cooperating cylinders, as to provide for this. In the drawings the blanket cylinder is shown as one-half the diameter of the impression cylinder, and consequently only two plungers are illustrated. It is to be understood however than any number of plungers may be employed, as governed by the relative sizes of the cylinders and the number of gaps to be balanced. The bearer surfaces 3' of the blanket cylinder need not be continuous, since it is only necessary that they be provided at the gap in the blanket cylinder where they will engage the plunger 13 of the impression cylinder.

The bearer surfaces and the cooperating plunger or pressure exerting mechanisms have been illustrated as applied, respectively, to the blanket cylinder and the impression cylinder. However, this application may be reversed, if desired, this being governed by the structural features of the press and the arrangement of the printing cylinder.

In the drawings, the impression cylinder 10 is shown as having a surface 12 formed thereon. In the preferred embodiment, this surface 12 has a diameter slightly less than the diameter of the main part of the impression cylinder 11, so that the pressure between the two cylinders, 11 and 10, is carried by the surfaces of the main bodies of said cylinders, or by the paper, at all times except when the gap 5 in the surface 2 is adjacent the surface 11, at which time the pressure is borne by the plunger 13 and bearer surface 3'.

As will now be apparent, the invention provides for bearer surfaces attached to or embodied in one of the cylinders of a printing machine which will cooperate with plungers or other resilient pressure exerting devices associated with the other cylinder of a couple, these pressure exerting devices and cooperating surfaces being so arranged as to provide additional pressure between the two cooperating rotating cylinders at all times when the paper and the printing blanket or plate are interrupted, so as to maintain a substantially constant pressure. In this way pressure variation and consequent vibration are eliminated or reduced to a minimum. While it is preferred to utilize resilient members of the type shown and to associate the same with the impression cylinder, such members may be associated with the plate or blanket cylinders, if preferred, and other means for applying resilient pressure between the printing couples may be utilized without departing from the invention in its broader aspects.

What I claim is:

1. In a printing couple including a cylinder having a gap in the surface thereof, the combination of rigid concentric bearer means for said cylinder, and resilient means associated with the other cylinder of said couple for exerting radial pressure against said bearer means over a restricted arc in axial alignment with the gap when said gap is at the impression point.

2. In a printing couple having cooperating impression and printing cylinders, said printing cylinder having a gap in its surface, the combination of rigid concentric bearer means for one of said cylinders, and resilient means incorporated in the other of said cylinders for exerting radial pressure against said bearer means over a restricted arc in axial alignment with the gap when said gap is adjacent the surface of said impression cylinder, whereby substantially con-

stant spacing and pressure between the cylinders is maintained.

3. In a printing couple having cooperating impression and printing cylinders, said printing cylinder having a gap in its surface, the combination of rigid concentric bearers for one of said cylinders, and radially movable spring-loaded plungers incorporated in the other of said cylinders for exerting pressure against said bearers when said gap is adjacent the surface of said impression cylinder.

4. In a printing couple having cooperating impression and printing cylinders, said printing cylinder having a gap in its surface, the combination of rigid concentric bearer means for one of said cylinders, and resilient means for applying radial pressure against said bearer means over a restricted arc in axial alignment with the gap when said gap is opposite the impression cylinder whereby substantially constant spacing and pressure between the said cylinders is maintained.

5. In a printing couple including a cylinder having a paper-engaging surface extending partially around its peripheral surface and leaving a gap therein, the combination of rigid concentric bearer means for one of said cylinders, and resilient means cooperating with said bearers over a restricted arc in axial alignment with the gap for exerting additional pressure between said cylinders when said gap reaches the impression point.

6. In a printing couple including a cylinder having a paper-engaging surface extending partially around its peripheral surface and leaving a gap therein, the combination of rigid concentric bearer means for said cylinder, and resilient means embodied in the other cylinder of said couple cooperating with said bearer means over a restricted arc in axial alignment with the gap to increase the pressure between said cylinders when said gap reaches the impression point.

7. In a printing couple having cooperating impression and blanket cylinders, a blanket of rubber or similar resilient material covering the surface of said blanket cylinder, and a gap in the surface of said blanket cylinder at the point of attachment of said blanket to said cylinder, the combination of bearer surfaces for said blanket cylinder, and resilient means embodied in said impression cylinder engaging said bearer surfaces over a restricted arc in axial alignment with the gap when said gap is adjacent the surface of said impression cylinder for exerting additional pressure between said cylinders.

8. In a printing couple having cooperating impression and blanket cylinders, a blanket of rubber or similar resilient material covering the surface of said blanket cylinder, and a gap in the surface of said blanket cylinder at the point of attachment of said blanket to said cylinder, the combination of rigid concentric bearer surfaces for one of said cylinders, and radially movable spring-loaded plungers embodied in the other of said cylinders for exerting pressure against said bearer surfaces when said gap is adjacent the surface of said impression cylinder.

9. In a printing couple comprising a pair of cooperating rotatable cylinders, an impression surface on one cylinder, a printing surface on the other cylinder, the said printing surface having a gap which periodically passes adjacent to the impression cylinder when the cylinders are rotated, and a resiliently supported member in one of the cylinders arranged to exert pressure in a

radial direction and to engage a bearer surface on the periphery of its cooperating cylinder during each such passage of the gap.
